UNITED STATES PATENT OFFICE.

CHARLES HODGES, OF GUIDEROCK, NEBRASKA.

LACE-MEASURING DEVICE.

SPECIFICATION forming part of Letters Patent No. 761,489, dated May 31, 1904.

Application filed July 20, 1903. Serial No. 166,835. (No model.)

To all whom it may concern:

Be it known that I, CHARLES HODGES, a citizen of the United States, residing at Guide-rock, in the county of Webster and State of Nebraska, have invented a new and useful Lace-Measuring Device, of which the following is a specification.

This invention relates to an improved fabric winding and measuring machine, and has 10 for its object to provide a simple, inexpensive, and efficient device of this character by means of which cloth, lace, embroidery, and other fabrics may be readily reeled or transferred from skeins or packages and evenly wound 15 on suitable bolts or reels for convenience in handling.

A further object of the invention is to provide a novel form of reel for holding the lace or other fabric while the same is being transferred 20 and to provide means whereby the reel may be readily inserted in the skein or package without disarranging, tearing, or otherwise damaging the fabric.

A further object is to provide means for 25 removably supporting the bolt or cardboard on which the fabric is transferred or wound and to provide means for measuring and indicating the number of yards of lace or other fabric as the same is transferred.

30 A still further object of the invention is to provide a winding-machine, the relative disposition of the several parts being such as to permit the machine to be quickly and compactly folded when not in use, so as to take 35 up very little room and facilitate transportation or shipment.

The invention consists in the construction 40 and novel combination and arrangement of parts hereinafter fully described, illustrated in the accompanying drawings, and pointed out in the claims hereto appended, it being understood that various changes in form, proportion, and minor details of construction may be resorted to without departing from the 45 spirit or sacrificing any of the advantages of this invention.

In the accompanying drawings, Figure 1 is a perspective view of a winding and measuring machine constructed in accordance with

my invention. Fig. 2 is a detail perspective 50 view of the reel detached, showing in dotted lines the arms contracted for insertion in the skein. Fig. 3 is a detail sectional view of the register and supporting-frame. Fig. 4 is a detail view, partly in section, of the register 55 and operating-shaft. Fig. 5 is a side elevation showing the machine folded.

Similar numerals of reference indicate corresponding parts in all the figures of the drawings.

1 designates a base or support, to the opposite ends of which are pivotally mounted in suitable bearings 2 substantially U-shaped frames 3 and 4, consisting of horizontally-disposed rods 5, the opposite ends of which 60 are bent to form upwardly-extending arms 6 and 7. Secured in any suitable manner to the base are spring-clips 8, provided with openings or sockets 9, adapted to receive lugs or projections 9' on the rods 5 and by means 65 of which the pivoted frames are locked in an upright position. The ends of the arms 6 and 7 of the pivoted frame 3 are provided with brackets 10 and 10', in which is removably journaled the skein or reel shaft 11, said 70 shaft being provided with a series of annular grooves or channels 12, adapted to receive the spring-tongue 13 of the bracket 10', and by means of which the shaft is prevented from being longitudinally displaced. Secured to the 75 reel-shaft 11 is a fixed collar 14, provided with ears or lugs 15, between which are pivoted angularly-disposed rods 16, the opposite ends of said rods being pivotally connected to skein-supporting arms 17, which are in turn pivoted 80 to adjustable collars 18, secured to a cross-bar 19, slidably and adjustably mounted on the reel-shaft 11. The cross-bar 19 is provided with a set-screw 20, adapted to engage the annular 85 grooves or recesses 12 and by means of which 90 said bar may be adjusted longitudinally on the reel-shaft and clamped at any desired position. By sliding the cross-bar forward it will cause the rods 16 and arms 17 to contract or lie close to the shaft, thereby permitting 95 the package or skein of lace to be easily placed on the reel, and by moving said bar rearwardly the rods 16 and arms 17 will ex-

pand and hold the lace firmly on the reel while being transferred, as clearly shown in Figs. 1 and 2 of the drawings. The reel may also be adjusted to accommodate packages or 5 skeins of lace of different lengths by sliding the collars 18 backward or forward on the cross-bar, as the case may be, and clamping the same by means of set-screws 21.

Secured to the upright arms 6 and 7 of the 10 pivoted frame 4 are bearing-brackets 22 and 22', in which is journaled an operating-shaft 23, provided with a crank-handle 23', said shaft being split longitudinally, as shown at 24, forming a springing cleft adapted to receive 15 the bolt or cardboard 25, upon which the lace, cloth, or other fabric is wound, said board being securely clamped thereon by means of a collar or sleeve 26, fitting over the end of the shaft and clamping the split ends of the shaft 20 together. The bearing-bracket 22' is preferably formed of spring metal, so as to give slightly and permit the shaft to be easily inserted and removed therefrom, and secured to the arm 6 at a point adjacent said bracket is 25 an outwardly-extending pin or lug 27, which engages an annular groove 28, formed in the shaft, and prevents the same from being accidentally withdrawn during the winding operation. As a means for measuring and indicating the approximate number of yards of lace, cloth, or other fabric being transferred I provide a suitable registering mechanism 29, consisting of a casing 30, within which is rev- 30 olubly mounted an indicating-disk 31, provided with peripheral teeth or spurs 32, projecting in the path of a pin 33, secured to the shaft 23, said pin being adapted to engage the teeth and turn the disk the distance of one tooth at every revolution of the shaft, the 35 number of yards transferred being indicated at an opening 34 in the casing. The registering mechanism is secured in position by means of a threaded bolt or pin 35, on which the disk 31 revolves, one end of the bolt eng- 40 gaging the arm 6 of the pivoted frame, the opposite end thereof being provided with a clamping-nut, as shown. The casing 30 is preferably provided with an inwardly-extending flange 36, the lower portion of which is 45 provided with an opening adapted to receive a pin or lug 37, secured to the base or support and by means of which the casing is securely fastened thereto.

The construction of the device will be read- 50 ily understood, and the operation thereof is as follows: When it is desired to transfer lace, embroidery, or similar fabrics from the packages or skeins, in which state they are usually imported to save transportation 55 charges, duties, &c., the reel is first adjusted to accommodate the length of the package or skein by sliding the collars 18 backward or forward, as the case may be. The rods 16 and arms 17 are then contracted by sliding the bar 60 65 19 forward and inserted in the package, after

which said bar is moved rearwardly and clamped at the desired position, causing the arms to expand and hold the lace or other fabric at the desired tension on the reel. The board or bolt is inserted in the cleft in the 70 operating-shaft and the crank turned, causing the lace to be transferred and evenly wound on the board 15, the approximate number of yards transferred being measured and indicated by the registering mechanism. 75

The device may be readily and compactly folded for transportation or shipment by removing the reel, operating-shaft, and registering mechanism, releasing the clips 8 from engagement with the lugs 9, and folding the 80 frames 3 and 4 downwardly on the support or base, as clearly shown in Fig. 5 of the drawings.

From the foregoing description it will be seen that I have provided an exceedingly simple and inexpensive machine for transferring, 85 winding, and measuring various kinds of fabrics, which may be quickly set up for use and compactly folded, so as to take up very little room. 90

Having thus described the invention, what I claim, and desire to secure by Letters Patent, is—

1. In a device of the class described, a base, supporting-frames pivotally mounted thereon, a skein-holder rotatably mounted in one of the frames, and a winding-spindle journaled in the other. 95
2. In a device of the class described, a base, supporting-frames pivotally mounted thereon, a skein-holder rotatably mounted in one of the frames, a winding-spindle journaled in the other, and an indicator operated by the winding-spindle. 100
3. In a device of the class described, a base, supporting-frames pivotally mounted thereon, a skein-holder rotatably mounted in one of the frames and a winding-spindle journaled in the other, means for locking the pivoted frames, and an indicator operated by the winding-spindle. 105
4. In a device of the class described, a base, supporting-frames pivotally mounted thereon, an expandable skein-holder rotatably mounted in one of the frames and a winding-spindle journaled in the other, and means for locking the pivoted frames. 115
5. In a device of the class described, a base, supporting-frames pivotally mounted thereon, an adjustable skein-holder rotatably mounted in one of the frames and a winding-spindle journaled in the other, means carried by the spindle for clamping a board or bolt, and means for locking the pivoted frames. 120
6. In a device of the class described, a base, supporting-frames pivotally mounted on the base, an expandable skein-holder rotatably mounted in one of the frames and a winding-spindle journaled in the other, means carried by the spindle for clamping a board or bolt, 125
- 130

means for locking the pivoted frames, an indicator, and means carried by the spindle for operating the indicator.

7. In a device of the class described, a base, supporting-frames pivotally mounted on the base, a removable and expandable skein-holder rotatably mounted in one of the frames and a removable winding-spindle journaled in the other, means for locking the pivoted frames, and means carried by the spindle for clamping a board or bolt.

8. In a device of the class described, a base, supporting-frames pivotally mounted thereon, bearing-brackets secured to the frames, an expandable skein-holder rotatably mounted in the brackets on one of the frames and a winding-spindle removably journaled in the other, and means for locking the pivoted frames.

20 9. In a device of the class described, a base, supporting-frames pivotally mounted thereon, an expandable skein-holder rotatably mounted in one of the frames and a winding-spindle journaled in the other, means for locking the pivoted frames, and means for preventing longitudinal displacement of the skein-holder and spindle.

10. In a device of the class described, a base, supporting-frames secured thereto, a skein-holder having a pair of pivoted arms, the free ends of which are adjustable inwardly at an angle to each other rotatably mounted in one of the frames, and a winding-spindle journaled in the other.

35 11. In a device of the class described, a base, supporting-frames pivotally secured thereto, a shaft rotatably mounted in one of the frames and a winding-spindle journaled in the other, a transversely-disposed bar adjustably mounted on the shaft, arms adjustably secured to the bar, and angularly-disposed rods one end of each of which is pivoted to the shaft, the opposite ends of the rods being pivoted to the arms, and means for locking the pivoted frames.

40 12. In a device of the class described, a base,

supporting-frames pivotally secured thereto, an expandable skein-holder rotatably mounted in one of the frames and a winding-shaft provided with a longitudinal slot or cleft journaled in the other, a sleeve or collar fitting over the split end of the spindle, and a crank for operating the spindle.

50 13. In a device of the class described, a base, supporting-frames pivotally secured thereto, an expandable skein-holder rotatably mounted in one of the frames and a winding-shaft in the other, lugs or pins secured to the pivoted frames, and spring-clips secured to the base and adapted to engage the pins or lugs for locking the pivoted frames.

55 14. In a device of the class described, a base, supporting-frames pivotally mounted thereon, an expandable skein-holder rotatably mounted on one of the frames and a winding-spindle journaled in the other, an annular groove or channel formed in the spindle, a pin secured to the frame adapted to engage the groove, means carried by the spindle for clamping a board, and means for locking the pivoted frames.

60 15. In a device of the class described, a base, supporting-frames pivotally mounted thereon, a removable and expandable skein-holder rotatably mounted on one of the frames and a winding-spindle removably journaled in the other, an indicator detachably secured to the base and operated by the spindle, and means for locking the pivoted frames.

65 16. A skein-holder having a plurality of arms, each of which is adjustable laterally at one end and inwardly at an angle to each other at the opposite end to lessen the distance between said arms at the introducing end of the holder.

70 In testimony that I claim the foregoing as my own I have hereto affixed my signature in the presence of two witnesses.

CHARLES HODGES.
